UNITED STATES PATENT OFFICE.

CHARLES BURROWS, OF SCHENECTADY, NEW YORK.

RULING-MACHINE.

SPECIFICATION forming part of Letters Patent No. 674,434, dated May 21, 1901.

Application filed October 30, 1899. Serial No. 735,200. (No model.)

To all whom it may concern:

Be it known that I, CHARLES BURROWS, a citizen of the United States, and a resident of the city and county of Schenectady, in the 5 State of New York, have invented certain new and useful Improvements in Ruling-Machines, of which the following is a specification.

My invention relates to improvements in 10 ruling-machines shown and described in Letters Patent Nos. 568,235 and 568,236, dated September 22, 1896; and it consists in the devices and parts and combinations of devices and elements hereinafter described, and set 15 forth in the claims.

The objects of my invention are to provide in a ruling-machine and in combination with a pen-beam provided with ruling devices and adapted to be raised and lowered at pleasure 20 of an operator for convenience of adjusting the said ruling devices a vertically-moving bed which is automatically operated for carrying sheets of paper to the pen or pens of the machine and withdraw the same therefrom 25 at times and intervals as may be required by the character and kind of ruling to be given to the sheets, and also to provide mechanism by which the sheet-supporting bed may be automatically raised, so as to carry a sheet 30 to be ruled up to the pens, and there be held for a proper time and then be automatically lowered for carrying the sheet out of contact with the said pens or inking-rollers and be so held for such a time as may be required, before being moved up toward the pens for receiving ink therefrom when the ruling is to be resumed, and, further, to remedy the defects arising from a trembling of the pens or slight movements of the points of the same, 35 which to a degree attended the same when dropped down on the paper as heretofore when operated by the pen-beam and dropping from a raised position to the paper and checked as heretofore, so as to give to the pen-beam a shock which generally caused a quivering of 40 the pens.

Other objects and advantages of this invention will be fully understood from the following description and claims when taken in connection with the annexed drawings, in which—

Figure 1 is a side elevation of a ruling-ma-

chine embodying my improvements with so much of said machine and parts and devices thereof as is necessary to show the connection of the coöperating parts and devices 55 with the improvements in this invention. Fig. 2 is a plan view of the same.

Similar letters of reference refer to similar parts throughout both views.

In the drawings, A is the drive-shaft of the 60 machine. A' is a feed-roller mounted on said shaft, and a is the usual endless cloth carried by suitable rollers for carrying the sheets to be ruled. C is a revolving disk secured on shaft C' and carrying movable cams C² 65 and C³, which are adjustable at will on the peripheral portion of said disk. The mechanisms for gearing these above-mentioned parts together so that the said revolving disk and its adjustable cams may be properly re- 70 volved by the said drive-shaft are fully shown and described in my Letters Patent No. 568,235, above mentioned, and therefore unnecessary to be shown and described in this specification. 75

B is the pen-beam, arranged across the machine and supported from each end from the side rails of the frame of the machine by standards D, (one of which is shown in the drawings) which are adjustable and are fully 80 shown and described in my Letters Patent No. 568,236, above mentioned, and therefore unnecessary to be more particularly described. This pen-beam B is supported from standards D by means of a horizontal pintle 85 d, provided at each end of the said beam and working, respectively, in a suitable bearing-piece d', secured therewith with one of said pintles, as shown in Fig. 2, provided with screw-threads d², working in a screw-threaded 90 split nut D, provided with tightening-screw d³ and having a horizontal arm d⁴ working in sleeve D², which is longitudinally split and tightened by screw d⁵ and is provided with vertical stem D³, which is adjustable at will 95 in said standard D. This pen-beam is also provided at one end with arm B', which is pivoted by pivot b' on the upper side of said pen-beam and is adapted to be variously adjusted in vertical direction by means of screws 100 b² b³, so that its free end b⁴ may be depressed or elevated in relation to a suitable stationary

Figure 1 is a side elevation of a ruling-ma-

piece b^5 , secured to the frame of the machine and serving as a support to said free end of said arm B' , whereby the pressure of the ruling device carried by the pen-beam may 5 be increased or lessened by means of the said adjusting-screws $b^2 b^2$.

E is a movable bed which is adapted to be moved vertically in direction upwardly and toward and to the pens b and downwardly 10 and away from said pens at times and intervals as the character and kind of ruling of sheets of paper may require, and any suitable mechanism arranged between said vertically-moving bed E and the revolving disk 15 C and adapted to be operated by cams C^2 and C^3 may be employed for moving said bed toward the pens b and holding the sheets supported thereon in contact with the said pens and for effecting a lowering of said bed that 20 the sheets may be carried out of contact with the same. This vertically-moving bed E may be of any suitable material, as of metal or wood, or both combined, as may be preferred, and be made with any suitable length and 25 width to adapt it for service in the machine for supporting sheets of sizes to be ruled. It is supported from the side rails of the frame of the machine or any stationary piece secured thereto by arms F , one at each end of the bed. 30 Only one of these arms is shown in the drawings, as each arm is a duplicate of the other and a description of one will suffice for the other. The forward end portion f of the arm F is secured, by means of bolts or screws $e e$, 35 to the said bed, preferably by being applied to the end of the same, and its rear end portion f' is pivoted to the side rails D' (one of said rails only is shown) by a suitable pivot F' . The forward end of each said arm is 40 provided with an outwardly-projected horizontal flange F^2 , preferably integral with portion f of said arm, as shown in Fig. 2.

G is a suitable rock-shaft extending from one side of the machine to the other and 45 supported from the end journals in suitable bearings G' , (one only shown,) provided with the side rails D' , to which they are secured from their upper sides. With these bearings G' are provided a lug g , having a screw-threaded hole g' , (indicated by dotted lines in Fig. 1,) which receives the adjusting-screw G^2 (shown in Fig. 1) to be provided with jam-nut g^2 .

Rigidly secured to each end of the rock-shaft G , at near the forward end of the bed-supporting arms F and beneath the flange F^2 , are arms H , integral with suitable hubs h , which arms are each a duplicate of the other and of which one arm H only is shown by 55 full lines in Fig. 1 and indicated by full and dotted lines in Fig. 2. Secured to the rock-shaft G at a point opposite the periphery of the revolving disk C is the pendent arm J , integral with hub j , by which it is secured to 60 shaft G . The lower end of this pendent arm is preferably provided with friction-roller J' ,

which is about opposite said periphery. Secured to the same end of rock-shaft G and adjoining the pendent arm J is the gage-arm K and keeper-arm L , both of which are preferably integral with hub k , by which they are secured to the rock-shaft. These several arms H , J , K , and L are so secured to the rock-shaft G that they may move with the same and also so that when either one of the 70 same is moved by its operating mechanism provided the other arms will be correspondingly moved, as will be hereinafter described.

Secured to the side rail D' and in part opposite the revolving disk C is the latch-frame 80 M , provided with latch N , pivoted to the former and having at its rear side a reacting spring M' , (indicated by dotted lines in Fig. 1,) all similar to the latch and frame and reacting spring shown and described in my Patent No. 568,235 before mentioned. This latch N is provided on its outer side with the inclined projection P , which is situated in the length of the latch, so as to be in the line of the circle in which the latch-operating cam C^2 85 (shown in the drawings) is carried by the revolving disk C . This latch is also provided with stop Q . (Shown by full lines in Fig. 1 and indicated by dotted lines in Fig. 2.) When in the revolution of disk C the cam C^2 is carried inwardly in direction from the inner side of said disk, the keeper-arm L will by the weight of the vertical moving bed E and its pivoted arms F , imposed on arms H , move said arm L to the front of stop Q 90 at the instant the latch N is moved inward by the action of cam C^2 on the projection P , and arms H will be lowered and gage-arm K will be raised to dotted lines and strike against the lower end of the adjusting-screw G^2 , 95 which limits the drop of the said arms H , and consequently that of the bed E , from the pens b , and so long as the keeper-arm L is in front of the said stop Q the said bed will be down and out of contact with said ruling devices and all the said arms will be in position of dotted lines, indicating their changed positions. When in the revolution of the revolving disk C the adjustable cam C^3 , which is 100 shown in Fig. 1 to be projected beyond the periphery of said disk, is carried against friction-roller J' , pivoted on the pendent arm J , said arm J will be moved back from dotted lines in Fig. 1 to that of full lines and so turn the rock-shaft that it will carry the gage-arm K 105 to full lines and away from the adjusting-screw and arms H upwardly, so as to move the bed E up, so as to carry the paper thereon into contact with the pens b , which latter is so well known as not to require any particular description. When said arms J , K , and H have been so moved to full lines, the keeper-arm L will have been moved from position 110 in front of stop Q and from pressing in said latch through said stop Q , and its front side 115 edge will be brought to the rear side of said stop, when the reacting spring M will push 120

the latch forward and carry said stop Q in engagement with said keeper-arm L, and thereby lock the rock-shaft from moving and the paper-supporting bed in raised position, as shown.

The drawings show by full and dotted lines two similar adjustable cams C² and two similar adjustable cams C³ secured to the rim of disk C, the former for operating with the inclined projection on the latch N and the latter for actuating arm L on the rock-shaft. These cams C² C³ may be each used in number of one or more, as may be required, and may be variously set and adjusted at pleasure on the rim of the disk as may be necessary as the ruled ink-lines to be produced on the paper supported on the bed may require for length, continuity, beginning, and stopping of the same.

20 The gate for regulating the feed of sheets of paper and tapes for carrying the same beneath the ink-ruling pens or rollers and other devices employed in ruling-machines are omitted from the drawings and this description, as they do not form any part of this invention, and these devices and mechanisms in my preferred form are clearly shown and described in my patents above mentioned and therefore do not require any further description. It is to be understood that the movable bed-piece may be variously changed or modified in its form of construction and proportions and that it may have its rearward portion supported in various ways without changing or affecting its operation or that of parts and devices employed with said bed in this invention.

My above-described improvements operate to allow the ruling devices carried by the pen-beam to be readily and nicely adjusted in relation to the paper to be ruled, so that a suitable contact of the former with the latter may be had without any imposition of an excess of pressure of the ruling devices on the paper over that required to mark the same and also operate to remove the cause of trembling of the ruling devices arising from shocks heretofore attending the sudden stoppage of the drop of the pen-beam carrying the said ruling devices, which shocks were generally consequent from the jar communicated to the pen-beam from the striker or striker-bar heretofore employed when that device falls in place on the rest which is provided to stop the fall of said striker or striker-bar.

Having described my invention, what I claim, and desire to secure by Letters Patent, is—

1. In a ruling-machine the combination 60 with a beam provided with a ruling device, of a vertically-movable paper-supporting bed adapted to be automatically raised and lowered at arbitrarily-adjusted intervals in relation to the speed of movement of the paper being ruled, as set forth.

2. In a ruling-machine the combination with a beam provided with a ruling device,

of a vertically-moving paper-supporting bed, mechanism for automatically raising said bed and mechanism for automatically lowering 70 the same at predetermined intervals as set forth.

3. In a ruling-machine the combination with a beam provided with a series of ruling devices and a revolving disk, of a vertically-movable paper-supporting bed and mechanism between said bed and said disk adapted to lower said bed to a plane below the plane of the lower point of said ruling devices, and mechanism also between said bed and revolving disk adapted to move the former upwardly 80 to the contact-points of said ruling devices, as set forth.

4. In a ruling-machine, the combination with one or more ink-ruling devices, a beam 85 carrying the same, pintles supporting said beam for convenience in adjusting said ruling devices, and a vertically-movable paper-supporting bed below the plane of the points of contact of said ruling devices with the paper on said bed, of automatic mechanisms 90 which are adapted at intervals to alternately lower and raise said bed, as set forth.

5. In a ruling-machine, the combination with a pen-beam, ruling devices carried by 95 said beam, a rock-shaft below the plane of said pen-beams and arms secured to the opposite ends of said shaft, of a vertically-movable paper-supporting bed between said pen-beam and rock-shaft and the arms supporting said bed, and mechanisms adapted to automatically raise and lower alternately and at intervals the said arms, as set forth.

6. In a ruling-machine, the combination with a vertically-movable paper-supporting 105 bed and a rock-shaft and arms which support the forward portion of said bed, of a gaging-arm secured to said rock-shaft and an adjusting-screw coacting with said gaging-arm and adapted to limit the drop of said bed-supporting arms, as set forth.

7. In a ruling-machine, the combination with a vertically-movable bed, a rock-shaft, bed-supporting arms secured to said shaft, a gaging-arm also secured to said rock-shaft 115 and an adjusting-screw cooperating with said gaging-arm for limiting the drop of the said bed-supporting arms, of an arm, also secured to said rock-shaft, adapted to be moved at intervals in a direction which may effect a raising of said bed-supporting arms, and subsequently be moved in an opposite direction which may effect a lowering of the said bed-supporting arms, as set forth.

8. In a ruling-machine, the combination 125 with a vertically-movable paper-supporting bed, a rock-shaft, bed-supporting arms secured to said shaft, a gaging-arm secured to said shaft and an adjusting-screw limiting the oscillatory movement of said rock-shaft, 130 of arm J adapted to operate said rock-shaft in one direction, arm L also secured to said rock-shaft and a latching device adapted to coöperate with said arm to hold said rock-

shaft and the bed-supporting arms to position moved to by the movement of the arm J, as set forth.

9. In a ruling-machine, the combination 5 with a paper-supporting bed and bed-supporting arms connected with a rock-shaft, and the arms L and J also secured to the same rock-shaft, of a latch provided with stop Q adapted to engage with said arm L for holding said bed-supporting arms in a raised position when said arm J has been moved in proper direction for carrying said arm L to the rear side edge of said stop, as set forth.

10. In a ruling-machine, the combination 15 with a paper-supporting bed, a rock-shaft and bed-supporting arms H secured to the same, and the arms L and J also secured to said rock-shaft, of a latch provided with stop Q adapted to engage with said arm L when said 20 latch is in normal position, a movable device adapted to press said latch and said stop in direction from said movable device and said stop out of engagement with arm L and thereby allow the gravity of the bed to move said 25 arm L forward and permit the bed-supporting arms to drop also by force of the gravity of said bed, as set forth.

11. In a ruling-machine, the combination with a vertically-movable paper-supporting bed, a rock-shaft, bed-supporting arms H and 30 arms L and J secured to said rock-shaft so as to move with the same and a latch provided with inclined projection P and stop Q, of a revolving disk, one or more adjustable cams C² and one or more adjustable cams C³ carried 35 by said revolving disk, as and for the purposes set forth.

12. In a ruling-machine, the combination with a vertically-movable paper-supporting bed, a rock-shaft, bed-supporting arms H and 40 arms J, K and L secured to said rock-shaft so as to move with the same, an adjusting-screw coöperating with arm K for limiting the movements of all the other arms connected with said rock-shaft, and a latch provided 45 with inclined projection P and stop Q, of a revolving disk, one or more adjustable cams C² carried by said disk and one or more adjustable cams C³ also carried by said disk, as and for the purposes set forth.

CHARLES BURROWS.
